UNITED STATES PATENT OFFICE

WILLIAM ELMER, OF PHILADELPHIA, PENNSYLVANIA

RAILWAY SECTION CAR

Application filed April 11, 1931. Serial No. 529,355.

My invention relates to cars of a type adapted for use by section and repair men on the railroad, and the various novel features thereof may be applied to a motor propelled car, or a hand car, or a trailer.

With cars of this general type, which I prefer to designate as "section cars", it is sometimes convenient to use the superstructure for seating workmen, in which case it is 10 desirable to afford the maximum seating capacity within the space available; and at other times it is convenient to use the superstructure as a platform upon which such materials as rails, joint bars, tools or other rail- 15 way equipment may be carried from one point to another.

Accordingly, the primary object of the present invention is to provide a convertible section car which, when assembled in one 20 form, is particularly adapted for carrying men; and when assembled in another form, is particularly adapted for carrying material.

This invention is particularly characterized by the provision of a plurality of deck 25 sections and other members associated therewith adapted for alternate arrangement to afford, in the one case, a flat continuous deck, and in the other case, a stepped formation in which the deck sections and associated mem- 30 bers serve as seats and as back, leg and foot rests.

This invention is also characterized by the provision of collapsible members which, when the car is arranged to afford seats, serve 35 as hand rails for the men seated thereon and which, when the car is used for carrying material, may be housed beneath the deck.

This invention is further characterized by the provision of a box-like underframe which 40 is adapted to accommodate the hand rails referred to above when they are collapsed, and which may also accommodate tools such as those commonly used for track laying operations or the like.

Other objects and advantages characteristic 45 of my invention will become more fully apparent from the description hereinafter which has reference to one embodiment or example thereof as shown in the accompanying drawings.

Of the drawings:

Fig. I represents a side elevation, partly in section, of the car when used for carrying men.

Fig. II represents a similar view, partly in section, when the car is used for carrying material.

Fig. III represents an end elevation, partly in section, of the car when used for carrying men.

Fig. IV represents a similar view, partly in section, when the car is used for carrying material; and,

Fig. V represents an enlarged cross section taken as indicated by the lines V—V of Fig. I.

In the section car shown in the drawings, the underframe comprises side sills 1 and end sills 2, disposed in the form of a rectangle and preferably constituting aluminum channel beams. The side and end sills 1 and 2, together with a flat plate 3 attached to the bottom flanges thereof, form a box in which tools may be conveniently accommodated. A transverse I-beam 4 may also be inserted, as shown, at the center of the underframe. The running gear, comprising axles 5 and wheels 6, is shown secured to the underframe in a conventional manner. On the top flanges of the side and end sills 1 and 2, brackets 7 and 8 are mounted, these brackets affording pivotal connections for the deck sections of the superstructure. The deck sections and their associated members comprise a number of planks 9, 10, 11, 12 and 13, disposed longitudinally of the car and hinged (with the exception of the seat members 11 which are stationary) to the underframe and to each other in such manner that when folded they form a continuous flat deck, as shown in Figs. II and IV, and when unfolded they form a stepped formation, as shown in Figs. I and III.

The deck sections 10 are hinged to the brackets 7 at 14 and are adapted to be swung upward and outward from their horizontal positions shown in Fig. IV to the vertical positions shown in Figs. I and III where they form leg rests and abut against the ends of the sills 2. Pivoted to the deck sections 10

at 15 there are additional planks 9, which, when the car superstructure is converted to a flat deck, are folded on the underside of the sections 10, but which, when the sections 10 5 are swung outward to the positions shown in Figs. I and III, form foot rests and running boards for the car. Each deck section 11 is permanently attached to the underframe and serves as a seat for the lower tier of men 10 when the car is adapted for seating purposes. When men are seated on the seat members 11, their legs overhang the deck sections 10 and their feet rest on the foot members 9. Deck sections 12 are pivoted at one side to the 15 brackets 8, and at the other side they carry the seat members 13 hinged thereto at 16. When the deck sections 12 are in horizontal position, the seat members 13 are folded therebeneath as shown in Fig. IV. When 20 the deck sections 12 are swung upward to vertical position, the members 13 are swung upward to horizontal position to serve as seats for the upper tier of workmen. The deck sections 12 and seat members 13 supported 25 in the latter positions by part of the tubular railing equipment hereinafter described.

The deck sections 10 and 12 preferably comprise metal plates, and their top surfaces 30 may conveniently be provided with wearing strips extending transversely of the car to facilitate the sliding of heavy material, such as rails or ties, across the car. When the deck sections 10 and 12 are in horizontal position, they extend well clear of the running 35 gear at the sides and ends of the car, and accordingly there is no danger of striking the running gear when heavy material is slid on and off the sides or ends of the car.

It will be observed that when the various 40 deck sections and other members are folded to form a flat platform, those members 9, 11 and 13, associated therewith, which are beneath the platform, are nested between the underframe and the deck sections 10 and 12 45 in a minimum of space, and the platform is centrally supported in a bracket 17 mounted on the transverse I-beam 4.

The hand railings provided for the safety 50 and convenience of the men when the car is used as a passenger car comprise generally upright members 18, preferably in the form of pipes bent to substantially U-shape, and horizontal members 19 and 20 pivotally joined to the upright members by T-shaped 55 connections 21. The upright members 18 are attached to the end sills 2 by hinges 22, and, as shown in Fig. II, they are adapted to be swung inward and downward to collapsed 60 positions in which they rest upon the bottom plates 3 and are completely confined within the box-like underframe. The horizontal members 19 and 20 comprise telescoping tubes normally maintained in extended position by cotter pins 23. When it is desired 65 to collapse the hand railings, the central tu-

bular member 20 is, after removal of the cotter pins 23, telescoped over one of the end members 19 and the two parts are swung in an obvious manner about the corresponding upright member 18. Subsequently the three 70 members 18, 19 and 20 folded upon themselves are bodily swung inward and downward to the position shown in Fig. II.

The upright members 18 are bent outward 75 at 24 to clear the ends of the seat members 13. The hand railings may be collapsed while the deck sections 12 and seat members 13 are temporarily held aside by being folded together and swung outward. The hand railings are thus adapted to pass through the deck sections from the upper side to the underside. On each upright member 18 there is provided a cross bar 26, preferably joined thereto by welding. When the uprights 18 are swung upward to vertical position, they are flexed about their hinges 22 to positions slightly beyond the vertical and then, after the deck sections and their associated flat members have been unfolded to form seats, the uprights 18 are allowed to spring back into a truly vertical position. When the uprights 18 spring back in this manner, the cross bars 26 catch beneath the seat members 13 and serve to support these members in a horizontal position. Near the ends of the cross bars 26, each seat member 13 is formed with a shoulder providing an angular notch 25, as shown in Fig. V, the engagement of the upright members 18 in the notches 25 serving to maintain the deck sections 12 in vertical 95 position. Furthermore, the seat members 13 may be secured to each other by hooks 29. Accordingly, the railings and deck sections 100 co-operate in effecting the alternate arrangements of the car superstructure by which the car is in the one form adapted for seating workmen and in the other form adapted for carrying material.

To prevent the deck sections 10 when used 105 as leg rests, as shown in Figs. I and III, from swinging incident to motion of the car, I may provide suitable means, such as the pipes 27 and pins 28, for tieing the opposite sections together across the bottom of the underframe.

It will be apparent that the particular 110 means selected for bracing or holding the deck sections in their alternate positions and the particular manner in which the deck sections and hand rail members fold and unfold admit of considerable variation; and my invention contemplates various departures 115 from the form of the apparatus herein described and illustrated.

Having thus described my invention, I 125 claim:

1. In a railway car of the character described, an underframe, and a plurality of flat members thereon adapted for alternate arrangement to afford either a flat deck or a 130

stepped formation, including leg rests and running boards overhanging the wheels of the car.

2. In a railway car of the character described, an underframe, and a plurality of flat members thereon adapted for alternate arrangement to afford either a continuous flat deck or a stepped formation in which the flat members serve as seats and as foot, leg and back rests, with the foot and leg rests overhanging the wheels of the car.

3. In a railway car of the character described, an underframe, and a plurality of flat members hinged to each other and to the underframe and adapted for alternate arrangement to afford either a flat deck or a stepped formation in which certain of the flat members overhang the wheels of the car and are tied together beneath said underframe.

20 4. In a railway car of the character described, an underframe, and a plurality of flat members thereon adapted for alternate arrangement to afford either a continuous flat deck or tiers of seats.

25 5. In a railway car of the character described, a box-like underframe and collapsible members thereon serving as railings, said members being adapted to be folded and housed within said underframe.

30 6. In a railway car of the character described, a box-like underframe and railings attached thereto, said railings comprising upright and horizontal members adapted to be folded upon each other and to be collapsed to a position within said underframe.

35 7. In a railway car of the character described, an underframe, upright members pivoted thereon, horizontal members pivoted on said upright members, said members serving as railings and being adapted to be folded upon themselves and swung downward to a position within said underframe.

40 8. In a railway car of the character described, an underframe, upright members pivoted thereon and horizontal members comprising telescoping sections with a pivotal connection to said upright members, said members serving as railings and being adapted to be collapsed to a position within said underframe.

45 9. In a railway car of the character described, an underframe, a plurality of hinged deck sections, and a collapsible railing comprising members adapted to be folded upon themselves, and when thus collapsed to be housed beneath said deck sections.

50 10. In a railway car of the character described, an underframe, a plurality of deck sections and other flat members thereon adapted for alternate arrangement to afford either a flat deck or a stepped formation, and collapsible hand rails comprising members adapted to be folded upon themselves and

when thus collapsed to be housed beneath said deck sections.

55 11. In a railway car of the character described, an underframe, a plurality of deck sections and other flat members thereon adapted for alternate arrangement to afford either a flat deck or a stepped formation, upright members pivoted on said underframe, and horizontal members pivoted on said upright members, said members serving as railings and being adapted to be folded upon themselves and swung downward to a position beneath said deck sections.

60 In testimony whereof, I have hereunto signed my name at Philadelphia, Pennsylvania, this 6th day of April, 1931.

WILLIAM ELMER.
